CLAIM

I claim the ornamental design for a large handled toothbrush, as shown and described.

DESCRIPTION

FIG. 1 is a perspective view of a large handled toothbrush according to the present invention.

FIG. 2 is a side view of the large handled toothbrush of FIG. 1.

FIG. 3 is a top view of the large handled toothbrush of FIG. 1; and,

FIG. 4 is a bottom view of the large handled toothbrush of FIG. 1.

The front, rear, and side opposite that shown in FIG. 2 are the same in appearance as the side that is shown in FIG. 2.
